BORED CASTING HANDLING DEVICE

Noel C. Hill, Williamsburg, Ky.

Application March 9, 1951, Serial No. 214,654

2 Claims. (Cl. 294—97)

1

This invention relates to a casting tool, and, more particularly, to a tool for facilitating the handling and movement of metal castings.

A primary object of the invention is the provision of an improved tool including a handle whereby a casting having a bore therein may be more readily lifted and moved as desired.

An additional and more specific object of the invention is the provision of such a device provided with an eccentric for gripping the interior of a bore in such casting.

Still another specific object of the invention is the provision of improved means whereby the tool may be readily disengaged when desired.

Still other objects reside in combinations of elements, arrangements of parts, and features of construction, all of which will be more fully pointed out hereinafter, and disclosed in the accompanying drawing wherein there is shown a preferred embodiment of this invention concept.

In the drawings:

Figure 1 is a vertical longitudinal sectional view taken substantially through the center line of one form of tool embodying features of the instant inventive concept.

Figure 2 is an enlarged fragmentary sectional view similar to Figure 1 disclosing the lower end of the tool in operative relation interiorly of the bore of a casting or the like, and

Figure 3 is an enlarged sectional view taken substantially along the line 3—3 of Figure 1 as viewed in the direction indicated by the arrows.

Similar reference characters refer to similar parts throughout the several views of the drawings.

Referring now to the drawings in detail, there is shown at 10 a cylindrical member provided at its lower extremity with a vertically extending slit 11. The upper end of cylindrical member 10 is provided with a transversely extending handle 12. A bossed recess 14 is provided centrally of handle 12, and is threaded at its upper extremity to accommodate a threaded plug 15 containing a bore through which extends an operating rod 16.

The rod 16 is provided at its upper extremity above the handle 12 with an operating button 17 which is gripped by the user's hand in forcing rod 16 downwardly. The rod 16 is also provided with a collar 18 disposed below plug 15, the movement of the rod 16 and collar 18 being limited by the depth of recess 14.

The rod 16 extends through a bore 20 in cylindrical member 10 secured interiorly to the side wall of cylindrical member 10 adjacent slot 11 and is adapted to engage an eccentric 22 which

2

is pivotally mounted as on a pivot 23 seated in apertures in opposite sides of slot 11.

Normally biasing eccentric 22 to extending position outwardly through slot 11, and positioned on the opposite side of pivot 23 from the extremity of rod 16 is a pin 24 which is biased downwardly by a coil spring 26, the pin and spring being seated in a bore 27 interiorly of tubular member 10 and directly above slot 11.

From the foregoing the operation of the device should now be readily apparent. When it is desired to move a casting, as shown at 28, provided with a central bore 30 of a desired diameter, push button 17 is depressed which biases eccentric 22 against the pressure of pin 24 and spring 26 to the position indicated in dotted lines in Figure 1. The tubular member 10 is then inserted in bore 30, and pressure on operating button 17 released whereupon spring 26 and pin 24 bias the eccentric to the position disclosed in Figure 2, and in full lines in Figure 1, the point 31 thereof extending outwardly through slot 11 into engagement with the interior side wall of bore 30. Simultaneously, as lifting pressure is exerted on handle 12 the effect of point 31 is to bite into the interior of the bore while the heel of the eccentric simultaneously forces the opposite side wall of member 10 into frictional engagement with the opposite side of bore 30. Such engagement is retained as long as lifting pressure is exerted on handle 12, and when it is desired to release the tool from engagement with the bore it is merely necessary to press operating button 17 which again rotates the eccentric to the dotted line position disclosed in Figure 1 whereupon the tool may be readily withdrawn.

From the foregoing it will now be seen that there is herein provided a device which accomplishes all the objects of this invention, and others, including many advantages of great practical utility and commercial importance.

As many embodiments may be made of this inventive concept, and as many modifications may be made in the embodiment herein shown and described, it is to be understood that all matter herein is to be interpreted merely as illustrative, and not in a limiting sense.

In the claims:

1. In a casting tool a solid cylindrical member including a transverse handle and having a slot at one end thereof and a bore extending longitudinally therethrough, said slot extending angularly upwardly at one end thereof beyond the lower end of said bore, a lug pivotally mounted in said slot, a pointed extremity on said lug,

spring means normally biasing said pointed extremity outwardly of said slot, a rod extending through said bore, an operating button at one end of said rod, the other end of said rod normally abutting said lug on the opposite side of its pivot from said pointed extremity whereby pressure on said operating button serves to bias said lug into the upwardly angularly extending portion of said slot to retract the same within said cylindrical member.

2. The structure of claim 1 wherein the spring means comprises a bore having a closed end opposite the pivot of said lug from said first bore, a pin in said bore abutting said lug, and a com-

pression spring between said pin and the closed end of said bore.

NOEL C. HILL.
